UNITED STATES PATENT OFFICE.

EDWARD F. BEGTRUP, OF JERSEY CITY, NEW JERSEY, ASSIGNOR TO METAL & THERMIT CORPORATION, OF CHROME, NEW JERSEY, A CORPORATION OF NEW JERSEY.

METHOD AND MEANS FOR LUTING MOLDS.

Application filed October 24, 1922. Serial No. 596,802.

To all whom it may concern:

Be it known that I, EDWARD F. BEGTRUP, a citizen of the United States, and a resident of Jersey City, in the county of Hudson and State of New Jersey, have invented 5 certain new and useful Improvements in Methods and Means for Luting Molds; and I do hereby declare the following to be a full, clear, and exact description of the invention, such as will enable others skilled in the art to which it appertains to make and use the same.

The invention relates to a novel method and means for luting or sealing molds made 15 of sand or the like, to prevent the material cast in the molds escaping between the parting surfaces of the mold sections, viz., the surfaces of the mold which are in mutual engagement, or in engagement with the surfaces of metal pieces partially enclosed and 20 extending outside of the mold. To this end, the invention comprises additionally compressing and condensing the molding material adjacent the parting surfaces of the 25 mold sections after the latter have been regularly formed and assembled, such additional compression being effected by providing the flask sections in which the mold sections are formed with flanges on their inner faces 30 adjacent the parting surfaces of the mold sections, forming the mold sections in the flask sections with their parting faces projecting a slight distance beyond the marginal edges of the flask sections, assembling the 35 mold sections, and applying pressure to the flask sections to force the latter together; thereby causing the material of the mating mold sections between the parting faces and the flanges to be strongly compressed and 40 the parting faces to be forced together or into engagement with the faces of the metal pieces under sufficiently heavy pressure to prevent the escape of fluid material poured into the mold.

45 The invention is illustrated in the accompanying drawings, in which,

Fig. 1 is a perspective view of a half-flask or box section adapted to be used in the operation of welding the ends of girder rails together by means of superheated molten steel or iron;

Fig. 2 is a side elevation of one-half of a mold section in course of preparation;

Fig. 3 is an end elevation of the mold as 55 initially applied to the rail ends;

Fig. 4 is a side elevation of the same;

Fig. 5 is a view similar to Fig. 3, showing the application of the clamping means for compressing the mold material to effect the luting or sealing;

Fig. 6 is a horizontal section on line 6—6 of Fig. 5.

It will be understood that the particular exemplification of the invention as represented in the drawings is that of a mold for effecting the welding of the ends of rails or the like by means of superheated metal poured into the mold which surrounds and encloses the rail ends, and in the description of the particular invention it will be understood that the same principles of construction and operation apply to any mold involving separable sections formed of compacted loose material, such as sand, or an admixture of sand and clay, or other materials ordinarily used for this purpose.

Referring to the drawings, 1 indicates one half of a mold box or flask, comprising side walls 2, 2, a bottom 3, and a reinforcing band 4, preferably formed of angle iron, connecting and spacing the top edges of the side walls 2, 2. The front edges of the side members 2 are cut out to provide openings 5 conforming to a half vertical section of the rail to be welded, and the rear of the casing is left open.

Secured to each of the inner faces of the side walls 2, 2, and spaced from and generally parallel with the edges of the openings 5, is a flange 10 normal to the surface of the corresponding wall 2. It will be understood that two of these flask sections, similarly constructed, are employed in forming the welded joint between rail ends by the method hereinbefore indicated, and that these two flask sections containing the mold-forming material are clamped about the rail ends, in which position the flanges 10 on the side walls of each flask section will constitute continuous rims substantially conforming to the cross-section of the rail and spaced from the rail at all points, as more particularly indicated in Figs. 3 and 5.

In constructing the mold proper, each half flask section is placed on a backboard 6 with a pattern "X," defining one half of the mold cavity, resting on the backboard and extending through the registering openings 5 in the front edges of the flask section. The flask section is elevated from the top

surface of the backboard by placing spacers or shims 7 under the edges of the flask section, as shown in Fig. 2. The sand or other refractory material is then filled into the flask section and thoroughly rammed or tamped therein to completely fill the flask section and extend beyond the front edges thereof, as at 8, a distance equal to the thickness of the shims 7.

10 When the two mold sections have been thus formed, the flask or box sections containing the same are placed about the ends of the rails which are to be welded together by the superheated molten metal poured into 15 the cavity 25 (see Fig. 6) which surrounds and separates the ends of the rails.

With particular reference to Fig. 3, it will be noted that when the mold sections are brought into initial engagement with 20 the rail ends, the projecting portions 8 of the molds are in contact with each other and with the surfaces of the rail ends. The initial contact between the parting surfaces of the mold sections is not sufficient, however, to prevent the molten metal escaping, and in order to prevent this condition, it has been customary, heretofore, to provide special luting means, either on the outside of the flask sections covering the parting lines, or to apply strips of refractory material soaked in an adhesive, such as molasses, about the rail ends, so that when the sections of the split mold were pressed together the luting strips of asbestos or the like would be compressed between the adjacent faces of the rail sections and the mold surface to seal the joint in the mold against leakage. Both of these methods are objectionable, the first, because it frequently 40 results in the formation of fins caused by metal escaping from the interior of the mold, entailing a waste of the welding metal and also producing an unsightly joint; and the second, because of the difficulty of applying the sticky luting strips to the surface of the rail and the general objection to handling material of this character. It also frequently occurred that the luting means, as thus applied, would rupture or break, resulting in a leakage or "run-out" 50 of the molten material and a consequent defective or incomplete joint.

The present invention is effective in overcoming all of these difficulties, and also in 55 avoiding the application of separate luting means, the refractory material and the mold sections adjacent the parting surfaces being so applied as to produce an effective luting or sealing action at all points where leakage of the molten metal would be likely to occur. To produce this condition of the mold material, at and adjacent the parting surfaces of the mold, the flask sections 1 surrounding the rail ends, as shown in Fig. 63, are forced toward each other by suitable

clamping means, here exemplified as U-shaped yokes or straps 15, each having secured to its legs a cross-head 16 carrying a compression screw 17 engaging a threaded socket 18 therein, which screw engages 70 a foot-piece 19 on a bar 20 bridging the sides of the walls 2, 2 of the flask sections. The compressive stress applied by these clamps to the flask sections has the effect of forcing the material of the mold sections 75 extending beyond the edges of the flask sections, which include the parting surfaces of the mold sections, backward toward the flask sections until the marginal edges of the latter come in contact with each other 80 and with the rail sections. It is evident that the mold material will readily move back into the flask sections at all points except where the flanges 10 are interposed. As these flanges project into the body of the 85 mold material, it is evident that the relative movement of the flask sections will cause a heavy compressive force to be exerted by said flanges on those portions of the material of the mold lying between said 90 flanges and the parting surfaces of the mold, or the surfaces of the rail ends. In other words, the entire body of the molding material enclosed within the continuous flanges 10 and the parting surfaces of the mold 95 sections, which are in engagement with each other or with the surfaces of the rail, is strongly compressed and condensed and the engaging surfaces maintained under sufficiently heavy contact pressure to prevent 100 any leakage of the molten metal delivered to the mold between the respective engaging surfaces of the mold, or between the engaging surfaces of the mold and rail ends.

Under certain conditions, the initial 105 clamping of the flask sections will produce a sufficient pressure between the protruding surfaces 8 of the mold to prevent leakage, but the latter condition is absolutely assured when the final clamping of the flask 110 sections is brought about, as the relative movement between the flask sections and the enclosed mold sections causes the flanges 10 to produce a very much heavier compressive force on the material of the mold confined between the flanges and the opposing surfaces of the rail ends, as illustrated in 115 Figs. 5 and 6. In this particular exemplification, it will be noted that the portions of the flanges 10, 10, overlying the head 120 of the rail and underlying the base of the rail are inclined in opposite directions so as to produce a vertical component of compressive force which will compact the material of the mold in these areas.

The description and illustration of the invention as applied to a mold for effecting the welding together of the ends of rails by the action of thermit steel or superheated steel produced in the electric furnace, is 125 130

merely exemplary, and, it will be understood that the invention is not limited to this particular field, but is applicable to all molding and casting operations involving 5 the use of split molds made of refractory material, such as sand or the like, which require the application of special luting means to prevent leakage between the parting surfaces of the mold, and by applying the 10 principles of construction and operation, as hereinbefore described, including the initial formation of the mold sections with portions protruding or projecting beyond the marginal edges of the flask, and providing 15 the latter with flanges to effect a super-compression of the molding material within the area defined by the flanges, it is evident that the material of the mold sections adjacent the parting surfaces will be com- 20 pressed and the mating surfaces pressed together with sufficient force to preclude any possibility of leakage of the material de- livered to the mold.

What I claim is:

- 25 1. The method of luting or sealing split molds of sand or the like which comprises additionally compressing the mold material adjacent the parting surfaces after the mold has been assembled.
- 30 2. The method of luting or sealing split molds of sand or the like which comprises forming the mold sections in separate flask sections with the parting surfaces projecting beyond the flask edges, assembling 35 the sections, and applying pressure to the flask sections to force the same together; thereby additionally compressing and condensing the mold material in the parting surfaces and forcing the latter into intimate 40 contact with the contiguous surfaces.
3. The method of luting or sealing split molds of sand or the like which comprises forming flask sections with flanges adjacent the parting surfaces of the mold, forming 45 the mold sections over patterns in the flask sections with the parting faces of the mold sections projecting beyond the marginal edges of the flask sections, assembling the mold containing flask sections, and applying 50 pressure to the flask sections to produce a relative movement between the same and the contained mold sections; whereby the material of the mold sections between the flanges and the parting surfaces will be 55 additionally compressed and said parting surfaces forced into intimate contact with the contiguous surfaces.
4. A mold comprising mold sections of tamped sand or the like having zones in 60 and adjacent the parting surfaces additionally compressed when the sections are assembled.
5. A mold comprising mating flask sec-

tions, and mold sections of sand or the like in the respective flask sections, said mold sections having their parting surfaces projecting beyond the marginal edges of the flask sections.

6. A mold comprising mating flask sections having flanges on their inner faces adjacent the parting surfaces of the mold, and mold sections of sand or the like in the respective flask sections, said mold sections having their parting surfaces projecting beyond the marginal edges of the flask sec- 75

7. A mold comprising mating flask sections having flanges on their inner faces adjacent the parting surfaces of the mold; 80 mold sections of sand or the like in the respective flask sections, said mold sections having their parting surfaces projecting beyond the marginal edges of the flask sections, and means for forcing the flask sections together.

8. A mold comprising mating flask sections having flanges on their inner faces adjacent the parting surfaces of the mold, mold sections of sand or the like in the respective flask sections having their parting 90 surfaces projecting beyond the marginal edges of the flask sections, and clamps engaging the flask sections for forcing the latter together.

9. A mold for forming welded rail joints 95 by means of superheated molten metal, comprising flask sections adapted to enclose the rail ends, refractory mold sections in the respective flask sections having portions adjacent the rails extending beyond the flask 100 edges, and means for forcing the flask sections together; whereby extra compression of the mold material at the parting surfaces will be effected.

10. A mold for forming welded rail joints 105 by means of superheated molten metal, comprising flask sections having flanges on their inner faces spaced from and substantially corresponding in shape to the contour of the rails, refractory mold sections in the respective flask sections having portions adjacent the rails extending beyond the flask 110 edges, and means for forcing the flask sections together; whereby extra compression of the mold material at the parting surfaces 115 will be effected.

11. A flask or casing for split molds comprising mating flask sections having flanges on the inner faces of their walls, said flanges being substantially normal to said walls, 120 spaced back from the mating edges of the sections, and substantially parallel with said edges and with the parting surfaces of the mold.

In testimony whereof I affix my signature.
EDWARD F. BEGTRUP..
